C. E. BLAKELY

CURTAIN ROD

Filed June 27, 1927

Inventor

Clarence E. Blakely

By Lynn H. Lath.

Attorney

UNITED STATES PATENT OFFICE.

CLARENCE E. BLAKELY, OF UTE, IOWA, ASSIGNOR OF ONE-HALF TO WILBUR A. BLAKELY, OF GRAND CENTER, IOWA.

CURTAIN ROD.

Application filed June 27, 1927. Serial No. 201,751.

My invention relates to curtain rods and has for its primary object to provide a curtain rod adapted to be attached to a window casing or the like without the use of screws.

- 5 A further object is to eliminate the usual brackets for supporting a curtain rod and to embody their function in an integral bracket member formed on the curtain rod itself.
- 10 More particularly it is my object to provide a curtain rod comprising two telescoping curtain rod elements, each of which is provided at its end with an integral bracket member adapted to serve as a clamp to frictionally engage the end edge of a window casing member, the curtain rod elements being provided with locking means for securing them against longitudinal extension and to thereby secure the clamp members in
- 15 frictional engagement with the window casing.
- 20 My invention further contemplates the use of such a structure in which the clamping engagement with the window casing is facilitated by the resiliency of the clamping bracket arms.

Another object of my invention is to provide a locking device contained within the telescoping curtain rod elements, together with means accessible from the exterior of said elements for actuating the same.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

40 Fig. 1 is an elevation of a portion of a window casing with my invention attached thereto.

Fig. 2 is a horizontal, sectional view through a curtain rod constructed according to my invention, the window casing member to which it is clamped being shown in plan.

Fig. 3 is a detail, sectional view taken on the line 3-3 of Fig. 2.

50 Fig. 4 is an enlarged, detail, sectional view of the locking device in disengaged position.

Fig. 5 is an enlarged elevation of one end of a window casing showing a portion

of the curtain rod and the clamping bracket.

Fig. 6 is a perspective view of the clamp- 55 ing bracket.

Fig. 7 is a longitudinal, sectional view of a somewhat modified form of my device.

Fig. 8 is a view of a further modified form of my device. 60

I have used the reference character 10 to indicate generally a window casing which has the horizontal upper casing member 11. The curtain rod of my invention comprises the usual tubular telescoping members 12 65 and 13, but instead of being supported by separate brackets, it is provided at its ends with integral clamp brackets including the arms 14, bent at right angles to the vertical plane of the curtain members 12 and 13 and 70 the clamp jaws 15, formed as continuations of the arms 14 and extended vertically to give an elongated clamping area. The jaws 15 are provided with pads 16 of rubber or 75 the like, designed to give a frictional gripping engagement with the ends of the casing member 11. The arms 14 have a certain amount of resiliency so that in locking the curtain rod elements 12 and 13 together, the 80 arms may be placed under tension.

For the purpose of locking the arms together, the outer curtain rod element 12 is provided with a series of indentations 17, formed in its inner wall, (Fig. 2) and the inner member 13 is provided with a lock 85 element 18, designed to engage in any one of the indentations 17. The locking element 18 has the shape shown in Fig. 4 comprising a curved lever portion 19, which fulcrums approximately at its center against the inner 90 wall of the curtain rod element 13 and which is curved at each end to form the cam surfaces 20 and 21. The end upon which the cam surface 21 is formed is hooked as shown in Fig. 4 to form the engaging hook 22. 95

A pin 23 limits the locking element against longitudinal movement, passing through an opening 24 in the locking element where it engages the wall of the curtain rod member 13, and being secured between the walls of 100 the curtain rod member.

A flat strip of metal, which may be termed a key, is used to actuate the locking element. This key is referred to generally by the character 25 and is provided at its inner end 105 with a narrow slot 26 to receive the pin 23

and a wider slot 27 to receive one end of the locking element 18. The juncture between the slots 26 and 27 form a pair of shoulders 28 and the block of metal between the shoulders 28 and the end of the strip serves as a cam to actuate the locking element. It may now be noted that by moving the key inwardly toward the locking element, the end of the key will engage the cam face 21, lifting the hooked end of the locking element into engagement with the depression 17. At the same time, the locking element will rock about its fulcrum against the inner wall of the curtain member 13 and its other end will move downwardly into the widened slot 27.

When the key is retracted outwardly, the shoulders 28 will engage the cam face 20, lifting the end of the locking element opposite the hook 22 and causing the locking element to rock so as to retract the hook 22 from engagement with its depression 17.

The key is extended through the end of the curtain rod member 13, being slidably received in a slot therein and may be provided with a finger engaging head 29 by means of which the key is operated.

In installing the curtain rod, the key is first pulled outwardly to retract the locking element and the telescoping curtain rod members 12 and 13, adjusted to the proper relative positions to correspond to the length of the casing member 11. Where a narrow window is involved, one person may grasp the two brackets with his palms against the brackets, insert them over the casing member 11 and thence apply pressure to the arms 14 so as to telescope the members 12 and 13 together as far as possible. In engaging the arm 14 at the end of the rod member 13, the thumb or one of the fingers is allowed to rest over the head 29. Simultaneously with the application of pressure to the arms 14, the thumb is allowed to exert a light pressure against the key so as to gently urge the locking element into engagement with the depressions 17. As the curtain rod elements are pushed together, the thumb or finger will be allowed to feel the movement of the locking element as it passes over the ridges between the succeeding depressions and when the curtain rod elements have been pushed together as far as they will go without injuring the brackets, the key will be forced inwardly and the pressure simultaneously released from the arms 14. The hook 22 will then slip back into one of the depressions 17 and will securely lock the curtain rod elements against opening. Other types of locking elements may be used, for instance, an integral finger might be employed, formed on the end of the member 13 and maintained in engagement with the notches 17 by the pressure between the arms 14. It may be noted in this respect that although

a snug fit has been shown between the telescoping curtain rod elements, that a small amount of play may be left between them and the locking element formed rigidly upon the end of the inner curtain rod member. The pressure between the arms 14 will maintain the inner end of the curtain rod element 13 against the inner wall of the curtain rod element 12 and the engagement of the locking member may be released by simply grasping the curtain rod near the inner end of the member 13 and pulling outwardly to cause the rod member 13 to move to a position against the outer wall of the member 12 instead of the inner wall. Such a construction is illustrated in Fig. 7.

The same principle operates in the preferred form of my invention shown in Figs. 1-6. The pressure between the arms 14 will cause the inner curtain rod member 13 to snugly hug the inner wall of the member 12 and there will be no possibility of the locking device becoming disengaged, due to the play that may develop between the curtain rod elements.

The form of my invention, illustrated in Fig. 8, is one applied to an open type curtain rod in which the curtain rod elements are C shaped in cross section with an open slot at the rear. The locking element 18^a is pivoted as at 18^b, in the curtain rod member 13^a and has a handle portion 18^c, between which and the forward wall of the curtain rod member, is received a spring 18^d, which tends to normally urge the locking hook into engagement with one of the number of slots 18^e in the curtain rod member 12^a. By inserting the fingers through the slots in the rear walls of the members 12^a and 13^a, respectively, the handle 18^c may be depressed to remove the locking member from engagement with its slot.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a device of the class described, a pair of telescoping curtain rod members provided at their outer ends with integral brackets including clamping jaws for engaging the ends of the casing member and means for locking the curtain rod members against longitudinal distension said means including a swinging, locking element carried by the inner curtain rod member at its inner end and the outer curtain rod element being provided with depressions to be engaged by said locking element and means for moving said locking element in and out of engagement with said depressions, said last

means including a key extending longitudinally through the end of the inner curtain rod element.

2. In a device of the class described, a pair of telescoping curtain rod members provided at their outer ends with brackets having clamping jaws, adapted to engage the ends of a casing member, the end of one telescoping member being adapted to engage and lock against the wall of the other telescoping member in any of a number of positions, so closely spaced as to enable the creation of tension between the brackets such as to result in pressure of the clamping jaws against the ends of said casing member, the brackets being semi-resilient so as to transform said tension into permanent pressure of the clamping jaws, the locking resulting from bending strain imposed upon the telescoping member by said tension and pressure.

3. In a device of the class described, a pair of telescoping curtain rod members provided at their outer ends with brackets having clamping jaws, adapted to engage the ends of a casing member, the end of one telescoping member being adapted to engage and lock against the wall of the other telescoping member in any of a number of positions, so closely spaced as to enable the creation of tension between the brackets such as to result in pressure of the clamping jaws against the ends of said casing member and friction elements carried by the clamping jaws and adapted to engage the ends of said casing member, the locking resulting from bending strain imposed upon the telescoping member by said tension and pressure.

4. In a device of the class described, a pair of telescoping curtain rod members provided

at their outer ends with brackets having clamping jaws, adapted to engage the ends of a casing member, the end of one telescoping member being adapted to engage and lock against the wall of the other telescoping member in any of a number of positions, so closely spaced as to enable the creation of tension between the brackets such as to result in pressure of the clamping jaws against the ends of said casing member and friction elements carried by the clamping jaws and adapted to engage the ends of said casing member, the brackets being semi-resilient so as to transform said tension into permanent pressure of the clamping jaws, the locking resulting from bending strain imposed upon the telescoping member by said tension and pressure.

5. In a device of the class described, a pair of telescoping curtain rod members, provided at their outer ends with brackets having clamping jaws adapted to engage the ends of a casing member, the telescoping members being adapted to interlock at any one of a series of positions and to thereby create a tension between the bracket members when the clamping jaws are in engagement with said casing member, resulting in pressure of the clamping jaws against the ends of said casing member sufficient to permanently support the device, the brackets being semi-resilient so as to adapt the clamping jaws to their proper positions relative to the casing member and to transform said tension into said pressure.

Signed this 25 day of June, 1927, in the county of Woodbury and State of Iowa.

CLARENCE E. BLAKELY.
